ATTORNEY

UNITED STATES PATENT OFFICE.

GEORGE E. HOWE, OF NORTH PLAINFIELD, NEW JERSEY.

HEADLIGHT.

Application filed May 6, 1925. Serial No. 28,312.

This invention relates to headlights such as are used on motor vehicles. The objects of the invention are to eliminate the objectionable glare ordinarily produced by such lights, without sacrificing the light values by diffusion, refraction or in other ways heretofore attempted; to concentrate the main light on the road and a lesser but sufficient illumination for the sides of the road and to accomplish these desired results with a simple, inexpensive and entirely practical apparatus, readily applicable to existing lighting structures.

The foregoing and other objects are attained in part by a novel form of reflector embodying an upper parabolic section for concentrating the light in a forwardly extending beam, a substantially crescent shaped lower reflector for directing the lower rays from the light source upwardly into the main parabolic section and a substantially upright crescent shaped reflector interposed between the parabolic and bottom reflectors for directing a portion of the light rays immediately ahead and to the sides of the roadway.

Various other novel features of the invention will appear as the specification proceeds.

In the drawing accompanying and forming part of this specification, one of the practical commercial embodiments of the invention is illustrated but it should be understood that the structure may be modified in various respects without departure from the broad spirit and scope of the invention as hereinafter defined and claimed.

Figure 1 is a vertical sectional view of the invention as in actual use.

Figure 2 is a front view of the reflector.

Experience has proved that the objectionable and dangerous glare caused by most headlights is usually produced by the lower half of the reflector which in actual practise often has the effect of throwing the light upwardly and directly into the eyes of oncoming drivers. The present invention takes recognition of this fact and involves the utilization of the upper useful section of the reflector and the replacement of the lower objectionable section of the reflector by reflecting walls which have no such effect but which do conserve the light and throw it all to useful purpose.

In the special reflector illustrated, the upper section 5 is termed the parabolic section, being designed to concentrate the upper rays

from the light source 6 in a forwardly extending beam, as indicated. This section is shown as terminating on a line 7 extending from points 8 at the rim of the reflector substantially on a level with the focal center downwardly to a point 9 somewhat below the center of the reflector, leaving a small segment 10 below the focal center tapering into the rim of the reflector.

From the lower edge of the parabolic upper section a substantially upright reflecting wall 11 extends down to the rearward edge 12 of an upwardly facing reflecting wall 13.

The lower reflecting section as shown in 70 the front view forms substantially a continuation of the circular rim of the complete reflector being deepest at the lowermost point and extending from a substantially horizontal position at such point upwardly into substantially vertical position at the sides of the same. The rear reflector similarly is deepest at the center, tapering gradually to the rim of the reflector and standing substantially vertically or inclined slightly toward 80 the rear throughout its full length.

The effect of these two substantially crescent shaped reflecting surfaces is indicated diagrammatically in the several views, from which it will be seen that the bottom 85 section 13 extending about the lower rim of the reflector catches practically all of the lower rays from the light source and reflects them into the upper section where they are concentrated and transmitted into a brilliant forwardly and downwardly projected beam. This lower section, which is substantially entirely out of line of vision of the approaching motorist, thus serves to 90 conserve and concentrate the light into useful effort without producing any glare.

The reflector is set so that the concentrated forward beam projected by the upper so-called parabolic section is directed onto the road at the proper distance ahead, the angle 100 being such as to prevent any glare effect from this section.

The reflector is of symmetrical form and as it need be no deeper than the parabolic section, it can be mounted in the so-called "drum" headlight casings now in use and indicated at 14. The three reflector sections may be formed integrally or in separate pieces suitably connected together, the structure in either case being relatively simple 105 and inexpensive. By saving the lower rays and transmitting them to the upper reflector

section, a materially intensified beam is produced which better illuminates the roadway without endangering other drivers. The narrow segment below the focal center aids 5 in the forward lighting effect but its useful extent is limited to about that shown.

What is claimed is:

In apparatus of the character disclosed, a reflector of completely circular outline at 10 the front to match a standard circular lens and comprising an upper parabolic section, a forwardly facing substantially vertical reflector section extending downwardly from substantially the axial plane of the upper section, a lower upwardly facing substantially horizontal section having its forward edge merging into and forming a continuation of the circular rim portion of the upper section, the forwardly facing section merging 15 into the circular rim between the lower edge of the upper section and the rearward

edge of the lower section, the line of connection between the upper and intermediate reflector sections extending from substantially the axis at the rim of the reflector 25 downwardly to a point below the focal center and said intermediate section being substantially crescent shaped to match said lower edge of the parabolic section and the rearward edge of the lower section, said lower section being deepest at the center and also of substantially crescent shape, the line of connection between the rear edge of the lower section and the lower edge of the intermediate section extending downwardly 30 and to the rear on an arc substantially conforming to the outline of the lower half of the circular rim.

In witness whereof, I have hereunto set my hand this 4th day of May, 1925.

GEORGE E. HOWE.
